UNITED STATES PATENT OFFICE

ADLAIE FISHER, OF HAVEN, KANSAS, ASSIGNOR OF ONE-HALF TO GEORGE D. MERRITT,
OF HAVEN, KANSAS

SNOWPLOW

Application filed March 7, 1930. Serial No. 433,946.

My invention relates to improvements in a snow plow.

The object of my invention is to provide a plow to remove snow from the highway.

5 A further object of my invention is to provide a snow plow that will deposit the snow on either side of the road.

A still further object of my invention is to provide a snow plow having a shovel with 10 a share positioned at right angles with the line of travel, the shovel having a mould board diagonally positioned thereon to avoid side thrust while the snow is being displaced.

A still further object of my invention is 15 to provide a V-shaped mould board carried by the shovel as means to throw the snow on each side of the highway simultaneously.

A still further object of my invention is 20 to provide an adjusting means for the rear end of the shovel.

A still further object of my invention is to provide a snow shovel conveyed by a tractor or the like and having a hoisting means therefor when transporting the same from 25 one place of activity to another.

A still further object of my invention is to provide adjustable wings for each side of the shovel element to form vertical or inclined banks as the snow is removed from 30 the highway.

These and other objects will hereinafter be more fully explained, reference being had to the accompanying drawings forming a part of this specification, in which like characters will apply to like parts in the different views and in which:

Fig. 1 is a side view of the snow shovel and fragmentary parts of the tractor.

Fig. 2 is a plan view of Fig. 1.

40 Fig. 3 is an inverted plan view of the shovel.

Fig. 4 is an enlarged perspective view of the brace and adjusting means for the rear of the shovel, parts removed for convenience 45 of illustration.

Fig. 5 is a rear end view of the mould board.

Fig. 6 is a side view of the rear end portion of the mould board and its attaching means.

Fig. 7 is an enlarged plan view of the apex 50 of the mould board and its attaching means.

Fig. 8 is a rear view of the apex attaching means.

Fig. 9 is a plan view of the shovel parts removed for convenience of illustration.

Fig. 10 is a side view of Fig. 9, showing one 55 wing turned downward.

Fig. 11 is a cross section of a highway showing different forms of the snow banks made by the plow.

My invention herein disclosed consists of a 60 shovel 1, having a share 2 attached to the front end thereof, as cleaving means for the snow from the ground while being conveyed along the highway or the like by a tractor, as shown fragmentarily at 3, in Fig. 1.

Positioned on the under side of the front end portion of the shovel element is a pair of runners 4, as carrying means therefor, the said runners being spaced apart and pivotally connected at their front ends and being adjusted as hereinafter described.

As a hitching means for the shovel portion of the plow to a tractor, a beam 5, is pivotally connected to each side thereof, in close proximity to the runner elements respectively as shown at A, the said beams extending rearwardly and being in parallelism with their respective sides of the tractor and having a cross bar 6, connecting the rear ends of said beams by which means the plow is hitched to a tractor as conveying means therefor, it being understood that the exact disclosure of the hitching means may vary as the case may require for the different makes of tractors.

Positioned on each of the beams in close proximity to the rear end of the shovel is a strut element 7 as carrying means therefor, the said struts being apertured as at 8 respectively, it being understood that the said strut members are in pairs and spaced apart as shown in Fig. 4 by which means the extended ends of the side carrying beams 9 will slidably engage on the outside thereof and being stationarily supported by a pin or bolt 10, engaging in the apertures of the struts and similar apertures in the extended end portions that will register with the first said apertures as the beams are rocked vertically to their selected positions.

Oppositely positioned to each shovel beam is a brace member 11, having one end secured to the beam 5, the other end to the upper extremity of the strut, by which means a truss is formed to carry the load imposed on the shovel without serious deflection of the said beam 5.

- i When transportation of the snow plow is required; the shovel portion thereof may be 10 elevated to a position shown by dotted lines B, in Fig. 1 through the medium of a cable 12 and a spool 13 on which the cable is wound, the said spool being trunnioned on a frame 14 and operated by a worm 15 having a shaft 15 as at 16 extending rearward therefrom and having a crank 17 as turning means therefor; it being understood that the said shaft is trunnioned on a suitable frame work as at 18 in Fig. 1, other means for the frame may be 20 employed to suit the style of tractor selected other than that shown in the drawings.

Positioned on the shovel element is a mould board 19, preferably made a V-shape, the apex thereof having a plate 20 attached thereto and being apertured as at 21 to receive a bolt as connecting means for the shovel, the rear ends of the mould board being secured to the said shovel by means of straps 22 respectively, the said straps extending across the ends and being secured to the shovel by nuts 23 threadedly engaging thereon by which the V-shaped mould board is easily placed and removed.

Intermediately positioned to the apex and rear end of the mould board is a bracing element 24 as means to resist the pressure imposed at either side thereof.

In the event of the road bed being irregular as to its surface or the earth miry; it may become necessary to raise the share of the shovel to avoid cleaving the earth. As a convenient means to raise and lower the same; the runners heretofore referred to are adjustably arranged by means of jack elements 26 positioned between the rear portion of the runners and the body of the shovel; the jacks being operated by shafts 27 and 28 respectively, the said shafts extending from their respective jacks in axial alignment and entering a housing 29 in which the same are trunnioned, it being understood that the said housing is securely affixed to the body of the shovel, and functions as an enclosure for bevel gears rigidly attached to the adjacent ends of the said shafts.

As a means to rotate the said shaft, a second shaft 30 positioned at right angles thereto is likewise trunnioned in the housing and has a beveled gear secured on the end thereof in mesh with each of the first said gears and by turning the latter described shaft by a wheel 30' on the outer end thereof, the said jacks are operated.

The rear end portion of each of the runners has a brace member 31 pivotally engaging on

a shaft 32 that axially aligns the adjacent ends of the brace members with the pivotally connected ends of the runners; the opposite ends of the brace members being secured to the free ends of the runners respectively, and rocked therewith simultaneously.

As a modification for the floor of the shovel, I have provided a wing member 33 hingedly connected to each side thereof, the outer edge of each of the said wing members diverging rearwardly and being so arranged that the bank of the snow will be vertical or inclined outward at the option of the operator as the plow is driven therethrough.

In Figure 9 is shown one wing of the plow positioned on a plane with the top side of the shovel, as means to slantingly position the bank of snow as shown at 34 in Fig. 11, while the wing on the opposite side of the shovel is dropped to a vertical position to 85 form a vertically disposed bank as shown at 35. The latter described position of the wing tends to trowel the wall to a compact smooth surface and the outer end portion of the mould board which extends over the side as shown at X in Fig. 9, will uniformly smooth the top of the bank as shown at 36, in Fig. 11.

While I have shown and described the wing members to be hingedly connected, I do not confine the assembly to that alone as they may be detachably arranged, but in either event competent bracing will be provided when the said wings are positioned on the plane with the upper face of the shovel, and such other modifications may be employed as lie within the scope of the appended claim, and what I claim as new and desire to secure by Letters Patent is:

In a snow plow of the class described comprising a shovel member and a V-shaped mould board carried by the shovel, each member of the mould board being perpendicular with respect to the plane of the shovel, a pair of beams pivotally attached to the shovel, a spaced distance from the share of the shovel, the other end pivotally engaging at the rear of a tractor as propelling means for the shovel, a strut upwardly extending and secured to each of the beams, the strut having a plurality of apertures spaced longitudinally therealong, a brace member attached to and extending forward from the rear end of each of the beams, the forward end of each brace and each of the rear corners of the shovel being carried by the struts at the tops thereof, by which means the upward slant of the shovel may be varied and a truss function obtained as a result of the assembly, the forward end of the shovel being carried and spaced from the ground by a pair of 125 arcuate runners, all substantially as shown.

In testimony whereof I affix my signature.

ADLAI E. FISHER.
